UNITED STATES PATENT OFFICE.

WILLIAM I. BUNKER, OF LAGRANGE, ILLINOIS.

CUSHION FOR SADDLES.

SPECIFICATION forming part of Letters Patent No. 674,451, dated May 21, 1901.

Application filed August 2, 1897. Serial No. 646,735. (No model.)

To all whom it may concern:

Be it known that I, WILLIAM I. BUNKER, a citizen of the United States, residing at La-
5 grange, in the county of Cook and State of Illinois, have invented a new and useful Im-
provement in Cushions for Saddles, of which the following is a specification.

My invention relates to that class of sad-
10 dles known as "velocipede" or "bicycle"
saddles, and has for its object the providing
of a simple, economical, and efficient cushion
therefor; and the invention consists in the
features, combinations, and details of con-
15 struction hereinafter described and claimed.

15 In the accompanying drawings, Figure 1 is
a perspective view of my improved cushion
looking at it from the top; Fig. 2, a trans-
verse sectional view taken through a com-
pleted saddle and cutting the cushion on line
20 2 of Fig. 1; Fig. 3, a top or plan view of a cushion,
showing the peripheral band extended,
so as to embrace or cover the upper surface
of the tissue or cellular resilient material con-
stituting the cushion proper; Fig. 4, a bot-
25 tom or under side view of the cushion shown
in Fig. 3, and Fig. 5 a longitudinal section of
a saddle complete with the cushion of Fig. 3.

In the art to which my invention relates it
30 is well known that there is considerable ob-
jection existing to saddles of the "rigid"
type, for the reason that the pneumatic tire
of ordinary construction does not take up all
35 the shocks or jars incident to riding and
many forms of saddles not having proper
means for ventilation become quickly heated
or overheated. My invention is primarily
40 intended to remove these objections and pro-
vide a simple, economical, and efficient cushioned saddle.

45 I prefer to make the cushion for my im-
proved saddle in the form shown in the draw-
ings, molded in shape to conform to a sup-
porting base portion and in that shape which
is known as "hygienic," this being best adapt-
45 ed for the purposes of riding. I make a lat-
tice-work A, arranged in a crisscross man-
ner, forming what I call "vertical open-end-
ed tubes or cells"—that is, tubes or cells open
50 at one or both ends, integral with each other,
and preferably held or bound together by a
circumferential rim or border B and an inner
rim b. It will thus be seen that each of these

tubes is capable of vertical and lateral com-
pression, forming, as it were, a multiplicity
of tubular cushions which yield locally to the 55
rider without distending or contracting other
portions of the saddle, and the tubes being
filled with air form practically an atmos-
pheric cushion of peculiar construction. This
provides for ventilation and when in use 60
makes a cool and comfortable saddle.

While I prefer to use both an outer and in-
ner rim, as shown, it will be understood that
either or both of these rims may be omitted,
as desired, and while I prefer to have the rims 65
or borders of the same width throughout, as
shown, it will be understood that they may
be made of varying widths or extended so as
to cover parts or surfaces not requiring free
70 ventilation.

The peripheral rim or border, where full
and free ventilation is not desired, can be ex-
tended so as to overlie or cover the entire up-
per surface of the resilient material consti-
75 tuting the cushion proper, and such construc-
tion is shown in Figs. 3, 4, and 5, where the
peripheral rim or border B is continued and
forms a top or cover B' over the entire sur-
face of the cushion proper, A, formed of the
multiplicity of vertically-extended tubes or 80
cells a, corresponding to the cushion proper
of Figs. 1 and 2. This construction does not
interfere with the combined vertical and lat-
eral movement and the simultaneous vertical
and lateral compression of the cushion, so as 85
to have the cushion yield locally to the rider
without breaking down or impairing the ef-
ficiency of any one tube or cell or any num-
ber of contiguous tubes or cells. The cushion
as a whole constitutes an atmospheric cush- 90
ion, and the continuation of the border or rim
over the tissue or cellular portion forming the
cushion does not impair or affect the cushion,
but merely continues the support of the bor-
der or rim over a greater area of space. The 95
cushion of Figs. 3, 4, and 5 is of the same
formation and construction except as to the
continuation of the peripheral border or rim,
as the cushion of Figs. 1 and 2, and has a wide
seat portion C, with a narrow projecting pom- 100
mel c, and an elongated central opening c',
with a peripheral wall b, comprising in these
respects the same parts as in the construction
of Figs. 1 and 2.

The complete saddle is to have an upper cover or covering of leather or some other similar rigid material and a lower cover or covering of similar material to the upper cover, 5 and the tissue of resilient material constituting the cushion proper is supported on a metal plate *e* and between the covers *D* and *D'*, and the covers are united at the edges *d*, as shown in Fig. 5.

- 10 The saddle is preferably made broader transversely at the seat portion *C* and with a narrow projecting pommel *c* and provided with an elongated central opening *c'*. As shown, it is formed or molded in the shape of
- 15 a compound curve to meet scientific and hygienic conditions and afford a safe and comfortable seat for the rider.

In forming the completed saddle the cushion is preferably inclosed in an upper leather covering *D* and a lower leather covering *D'*, 20 forming a complete closure, the covers being united at the lower edges *d* by the use of cement, rivets, or threads, as desired. The supporting-plate *e* is of course between the cushion and the lower leather covering.

The cushion proper, whether provided with a peripheral band or rim or with an extension over its upper surface, is composed of a tissue of individual cells or tubes, which are 25 arranged in such relation and are so joined and integral one with the other as to cause each individual cell or tube to support, by the union and conjoining of its walls with the walls of the adjoining cells or tubes, the adjoining cells and also to cause the adjoining cells or tubes through their walls to support the correlated cells. The arrangement is one 30 by which the continuity of the cells is unbroken both laterally and longitudinally, 35 and this construction enables the walls to be made very thin, so as to give the yielding or cushioning effect and at the same time have the continuity of the walls furnish a support against the crushing or breaking down of 40 any one cell or series of cells and to also furnish a support for the cells as a whole which will return any one cell or any number of cells back to normal condition after an excess of pressure is released. It will thus be 45 seen that the cushion is one which yields under pressure as required and which will not break down or crush readily and will return to its normal condition.

The cellular construction of cushion forming the essential feature of the invention is 50 one in which the cells have an integral relation one to the other, with a formation for each cell by which its walls or sides are free to corrugate, curl, or wrinkle under the effect 55 of a local pressure, each wall having the possibility of corrugating, curling, or wrinkling independently and of flexing, bending, or doubling without breaking the integrity and continuity of the cells as a whole, thereby 60 giving a different effect and a different result and action than is accomplished through 65 the ordinary compression of a resilient body.

The cells each have their surrounding walls or sides of a thickness the nature of which will permit the flexing or doubling or bending of a wall or side for giving a corrugating, 70 curling, or wrinkling of the material which will produce a resistance without any rending, breaking down, or giving away of the cellular tissue, and for this purpose, in order

75 to enable the flexing, bending, or doubling to be utilized in producing a corrugating, curling, or wrinkling, the cells should each be of a depth and breadth which will allow the walls or sides to corrugate, curl, or wrinkle, 80 and the depth may be greater than the width or breadth, and the width or breadth may be more than the lateral bend of the corrugation, curl, or wrinkle to which the cushion would be subject under pressure.

The action of the corrugating, curling, or wrinkling of the walls or sides is one that will permit the cushion to sink down locally under a resistance, drawing the adjoining cells bodily 85 toward the point of greatest depression and 90 placing the walls or sides of the cells adjoining the depression under a stretch or expansion which will operate to return the cushion as a whole to its normal condition when the local pressure is removed without any deteriorating or ill effect from the pressure.

The thickness of the walls will depend upon the depth of the cushion; but in any event the walls or sides are to be of a membranous 95 nature, with a sufficient thickness naturally to stand by themselves without deflecting and at the same time thin enough to yield without compression under a local pressure, and the degree of thickness can be varied so long as the wall or side is thick enough to 100 stand alone, and yet thin enough not to compress when subjected to a local pressure, but free to flex, double, or bend and have a corrugating, curling, or wrinkling given thereto under the pressure.

105 The principal advantages of my invention are that it may be economically made, readily fits the rider, is thoroughly ventilated, and yields or gives locally to conform to the anatomy of the rider, and generally to take up 110 the small vibrations or shocks not taken up by the ordinary pneumatic tire.

I claim—

1. In a saddle, the combination of a supporting base-plate, an inclosing cover, and a 115 cushion of resilient material, interposed between the cover and base-plate and having a body composed of a series of open-ended cells, formed by intersecting walls of a membranous nature having the capability of standing alone and the adaptability of curling or corrugating under pressure permitting the cushion to yield in use without collapsing or breaking down any individual cell, substantially as described.

2. A cushion comprising a tissue of individual cells or tubes formed of intersecting walls or strips of a membranous nature, having the capability of standing alone and the

adaptability of curling or corrugating and of supporting each other by their union, permitting the walls or strips to separately flex or bend and separately curl or corrugate under pressure, substantially as described.

3. A cushion for a bicycle-saddle made of resilient material and having a body divided by lateral and longitudinal vertically straight integral walls or strips crossing each other at right angles and forming a tissue of vertical cells or tubes having walls of a membranous nature with the capability of standing alone and the adaptability of curling or corrugating under pressure and supported against downward pressure and held against lateral and longitudinal yield of any one individual

cell by the tying together of the entire tissue of cells or tubes from the union of the crossing walls or strips, substantially as described.

4. A cushion formed of an essentially sensitive supporting-tissue of resilient walls, producing a honeycombed structure and having the walls of a membranous nature with the capability of standing alone and the adaptability of curling or corrugating under pressure and resuming their normal condition when the pressure is removed, substantially as described.
